UNITED STATES PATENT OFFICE.

ALFRED R. WOOD, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

NEEDLE THROAT FOR BUTTONHOLE-SEWING MACHINES.

Application filed December 28, 1923. Serial No. 653,062.

To all whom it may concern:

Be it known that I, ALFRED R. WOOD, a citizen of the United States, residing at Bridgeport, in the county of Fairfield and 5 State of Connecticut, have invented certain new and useful Improvements in Needle Throats for Buttonhole-Sewing Machines, of which the following is a specification, reference being had therein to the accompanying drawings.

Buttonhole sewing machines are commonly constructed with stitch-forming mechanism and a work-clamp which are relatively movable to carry the stitching around a 15 buttonhole. In some machines this relative movement, which is known as a travelling or feeding movement, is secured by moving the work-clamp and in others by moving the stitch-forming mechanism. The 20 stitch-forming mechanism commonly comprises upper thread mechanism and under thread mechanism; the upper thread mechanism including a reciprocating needle-bar carrying a needle and the under thread mechanism including suitable loop-taking and under thread carrying devices. The under thread mechanism is usually mounted 25 on a rotary turret to which the needle-bar an axial turning movement is imparted in sewing around the eye-end of a buttonhole. The rotary turret also carries a needle-throat member which supports the work 30 against the thrust of the needle and is commonly constructed in the form of a post having an overhanging upper extremity on 35 which is formed a small circular button-like raised portion perforated with a needle-hole.

The work-holder is usually split longitudinally into separable sections each of 40 which comprises a lower work-supporting plate and an upper clamping foot. The work-supporting plates are cut away along portions of their meeting edges to provide 45 clearance for the needle-throat member the upper or work-supporting surface of which lies substantially at the level of the work-supporting surface of the work-clamp sections. The upper clamping feet are shaped 50 to expose an area of fabric for the action of the needle and the buttonhole slit cutter.

In machines which cut the buttonhole after sewing it, the several plies of material

in which the buttonhole is stitched are necessarily firmly incorporated or bound together 55 around the buttonhole-slit by the previously formed overseaming stitches. Such buttonholes are sometimes objected to, however, on the grounds that the cut edges of the body-material protrude through the overedge 60 stitches and are not so well covered as are the edges of body-material in buttonholes which are first cut and then stitched. Buttonhole sewing machines have therefore been 65 constructed to cut the buttonhole before sewing it and it is to this latter type of machines that the present invention is particularly addressed.

In the operation of buttonhole machines 70 which cut before sewing, considerable difficulty has heretofore been experienced in sewing acceptable buttonholes in certain classes of material, such as spongy fabric or leather. The buttonholes are usually sewn 75 through a plurality of plies of body-material and interlining and the tendency is for the under ply to drag over and be scuffed or distorted by the needle-throat member; whereby the cut edge of the buttonhole slit is pushed to one side and out of the range of 80 the stitch-forming mechanism so that such cut edge is not caught in and covered by the overseam. This failure usually occurs in sewing around the eye and along the return side of the buttonhole.

It has been discovered that the convex leading edge of the needle-throat member 85 is primarily responsible for the failure of "cut first" machines to handle spongy work; the tendency being for such edge to scuff and deflect the under ply of material away from the buttonhole-slit so that the cut edge of 90 such slit will not be caught by the needle. Attempts have heretofore been made to overcome the difficulty by lowering the needle-throat member on the turret but this expedient removes the support from the edge 95 of the material at the sewing point and allows such edge to alternately yield or bend downwardly as the needle penetrates the material and rise with the needle as the latter begins its upward movement, thereby delaying the throwing out of the needle-loop and causing the machine to skip stitches.

It has been discovered that the difficulty 100 may be successfully overcome by providing

a needle-throat member, the raised work-supporting portion of which, instead of being substantially circular and having a convex leading edge, as heretofore, is made 5 pear-shaped so as to present a reentrant leading edge terminating in a leading point, which edge and point operate to scoop or deflect the under ply of the work toward the buttonhole-slit, whereby the cut edges will 10 be caught in the overseam and properly covered. The work-supporting surface of the needle-throat member is also preferably formed with a shallow groove leading upwardly and rearwardly or toward the 15 needle-hole from the reentrant leading edge to avoid an abrupt or harsh initial engagement of such edge with the under surface of the work.

In the accompanying drawings, Fig. 1 is 20 a transverse sectional view through the work-clamp of a buttonhole sewing machine showing the needle-throat member in front elevation when sewing down the return side of a buttonhole. Figs. 2 and 3 are respectively left and right side elevations of the 25 needle-throat member shown in Fig. 1. Fig. 4 is a top plan view of the needle-throat member. Fig. 5 is an enlarged section on the line 5—5, Fig. 4. Fig. 6 is an enlarged 30 section on the line 6—6, Fig. 4, with elements of the work-clamp and the stitch-forming mechanism added. Fig. 7 is a view similar to Fig. 5 with elements of the work-clamp added. Fig. 8 is a perspective view 35 of the needle-throat member from above. Fig. 9 is a perspective view of the needle-throat member and associated under thread mechanism from below. Fig. 10 is a diagrammatic view illustrating the action of 40 a needle-throat member of the prior art and Fig. 11 is a similar view illustrating the action of a needle-throat member embodying the present invention.

In the embodiment of the invention illustrated, 1, 1 represent the lower work-supporting plates and 2, 2 the upper clamping feet of a buttonhole sewing machine having stitch-forming mechanism such, for example 45 as that disclosed in the Allen & Faulkner Patent No. 1,372,473 of March 22, 1921, and including the reciprocating and laterally jogging needle 3 with which cooperates the under thread mechanism including the loopers 4, 5 carried by the usual rotary turret mounted in the curb or casing 6. Mounted upon the turret, as usual, is the needle-throat member in the form of a post 7, the overhanging upper portion 8 of which is 55 formed with a button-like raised portion 9 which, in the present instance, is pear-shaped and has a reentrant leading edge-portion 10 terminating at the leading point 11 which is preferably disposed outside of the zone α , Fig. 11, of the overseam. Back of the point 60 11 and reentrant leading edge 10 is a shal-

low groove or depression 12 sloping upwardly toward the needle-hole 13 and bordered at its outer side by the ridge 12' which is curved outwardly and forwardly from the needle-hole 13 and terminates at 70 the leading point 11 which is thus disposed at one side and in advance of the needle-hole 13. The needle-throat member is provided with the usual cord-hole 14.

It will be understood by referring to 75 Fig. 10 that the convex leading edge e of a needle-throat member of the prior art, travelling relative to the work in the direction of the arrow, will drag upon and push or deflect the under ply of material away from the buttonhole-slit, thereby stretching and distorting the material adjacent such slit. By forming the needle-throat member with a leading reentrant portion, substantially as described, the material within the 80 zone of action of the needle-throat member, Fig. 11, will be plowed or deflected toward the buttonhole-slit and will therefore be securely caught in the overseam and properly covered. When a buttonhole-slit is cut in 85 spongy material the cut edges tend to expand as shown at 15, Figs. 6 and 7, and the upwardly sloping shallow groove 12 gradually lifts the expanded cut edges into sewing position as the reentrant leading edge 90 10 and ridge 12' bordering the outer side of such groove plow or deflect inwardly the under ply of material.

Having thus set forth the nature of the 95 invention, what I claim herein is:—

1. A needle-throat member for cut-first 100 buttonhole sewing machines, said member having a needle-clearance aperture and means for deflecting the body-material towards the buttonhole-slit.

2. A needle-throat member for cut-first 105 buttonhole sewing machines, said member having a needle-clearance aperture and having a body-material deflecting surface inclined outwardly and forwardly away from the needle-aperture so as to cause deflection of the body-material toward the buttonholeslit.

3. A buttonhole sewing machine needle-throat member having a needle-clearance 110 aperture and a reentrant leading edge terminating at one side and in advance of the needle-clearance aperture in a leading point.

4. A buttonhole sewing machine needle-throat member having a needle-clearance aperture and a reentrant leading edge terminating in a leading point, said member being formed in rear of said edge with a shallow upwardly sloping groove.

5. A buttonhole sewing machine needle-throat member having a needle-clearance aperture and a reentrant leading edge terminating in a leading point, said member being formed in rear of said edge with a shallow upwardly sloping groove bordered 115 120 125 130

at its outer side by a ridge in rear of said point.

6. A buttonhole sewing machine needle-throat member comprising a post formed at 5 its upper end with a button-like elevation having a reentrant leading surface-portion adapted to deflect the body-material toward the buttonhole-slit.

7. A buttonhole sewing machine needle-10 throat member formed with an upwardly sloping groove bordered at one side by a

ridge adapted to deflect the body-material toward the buttonhole-slit.

8. A buttonhole sewing machine needle-throat member formed with a button-like 15 raised portion having a needle aperture and a leading point at one side and in advance of the needle aperture.

In testimony whereof, I have signed my name to this specification.

ALFRED R. WOOD.
